UNITED STATES PATENT OFFICE.

WILSON WHITELEY AND WATSON WHITELEY, OF RISHWORTH, NEAR HALIFAX,
ENGLAND.

PROCESS OF MAKING SEAMLESS TUBES.

Application filed January 8, 1923. Serial No. 611,865.

To all whom it may concern:

Be it known that we, WILSON WHITELEY and WATSON WHITELEY, subjects of the King of Great Britain, residing at Rishworth, near Halifax, in the county of York, England, have invented new and useful Improvements in Processes of Making Seamless Tubes, of which the following is a specification.

10 This invention relates more particularly to sliver or carding cans for carded or the like textile fibres, but it is equally applicable in the production of paper tubes of large diameter; and our object is to construct the 15 bodies of such cans, or of the large paper tubes, of a desirable thickness of material giving the necessary rigidity, perfectly cylindrical, seamless, and with a polished, glazed or perfectly smooth surface inside 20 and out, so that when embodied in a sliver can, the sliver does not when entering or leaving the same, come into contact with any projecting or uneven portion of the surface thereof likely to cause it to cling thereto, 25 consequently it is not liable to be stretched, thinned, or damaged at any part of its length, therefore a more even and better quality of yarn is ensured by its use.

Hitherto, the fibre bodies of these cans 30 have been made from the sheet, with overlapping side edges which are riveted or otherwise secured together. If these cans are made of tin the side edges are soldered together, in each case however the joint is 35 apparent and projections or unevenness occurs at this part, to which the sliver is frequently apt to cling and have some portion of its fibres torn therefrom in consequence, resulting subsequently in uneven and inferior yarn.

40 According to our invention, we construct or form our improved fibre tube upon an ordinary "board" machine. In accomplishing this we detachably mount upon the ordinary press roll of this machine, a smooth or seamless or the like metal tube having an internal longitudinal key engaging the corresponding and well known groove in the periphery of the press roll, whereby the two 45 revolve integrally.

The press-roll with its surrounding tube 50 are of such a diameter that the paper tube to be formed thereon, will possess the internal diameter desired. The web of web paper pulp is passed on to the tube covering

the press-roll and is wound thereon in a series of concentric layers in the customary manner until a desired thickness thereon is attained when the web is severed. The web is so thin that when the severed end is 60 pressed into engagement with the main body on the tube, it immediately merges therein and becomes unnoticeable and a part thereof. The metal tube with the wet paper tube thereon is now taken off the press-roll and 65 placed in any suitable place to dry. After attaining a suitable degree of dryness, the metal tube is placed upon a spare roll or drum and the latter mounted in the usual way and by well known means, between the 70 fast and loose heads of an ordinary screw-cutting lathe or the like, and a small roller with a preferable slightly convex periphery, carried by a suitable bracket or arm secured in the tool holder or the like of the cross 75 slide on a sliding carriage, is made by the means operating the said cross-slide, to frictionally engage the fibre tube upon the roller or drum.

Upon the lathe being started, the geared 80 head-stock revolves the drum or roller and with it the paper tube, and as the latter is in the desired frictional engagement with the small roller aforesaid, it revolves the latter also. The usual nut is next placed in 85 gear with the lead screw when the cross-slide and saddle are given a longitudinal traverse which is transmitted to the small roller, commencing at one end of the paper 90 tube and terminating at the other end thereof. The pressure of the friction roller upon the paper tube, and its rotary and longitudinal movements, exercise a smoothening and polishing effect upon the exterior of such tube, whilst the shrinkage of said tube during the drying process and the smooth exterior of the metal tube or arbor carrying 95 the same, exercise a corresponding effect upon the interior thereof, so that we are enabled to produce in this manner a paper 100 tube of a desired large diameter and of the requisite rigidity and strength, perfectly cylindrical with the desired smooth or glazed surfaces throughout, and capable of being adapted for use in the construction of 105 sliver cans of the kind desired.

The rolling of the paper tube as aforesaid, loosens the tube upon its support, so that upon taking the roller or drum out of the lathe it can be easily slipped off the same. 110

When the paper tube is taken off the metal tube, it is ready for the ends being trimmed or squared, varnished, and fitted with one seamless metal rim at one end and a corresponding base at the other end, to complete the can.

It will be obvious that the wet web may be run directly on to an arbored drum or roller instead of a tube mounted thereon, but 10 this method is not so economical.

We attain these objects by the means illustrated in the accompanying drawing, in which Fig. 1, is a cross-sectional view of our improved seamless or jointless paper 15 sliver-can or the like, constructed according to our invention; Fig. 2, is a similar view of the detachable metal tube carried by the press-roll, upon which is wound the wet paper web when manufacturing said cans; Fig. 3, is also a similar view of the ordinary press-roll of a board machine; Fig. 4, is a front view of Fig. 3 with metal and paper tubes thereon; and Fig. 5 is an end view showing the relative positions of the 20 roll or drum carrying the dried paper tube, mounted in a lathe, and the means for polishing the surfaces of the latter and detaching or loosening it upon its support.

Referring to the drawing in which similar letters refer to similar parts throughout the several views, A is the paper tube made of a number of concentric layers of a wet paper web wound upon a detachable tube B also keyed or otherwise secured to 30 the press roll C for the two to revolve integrally. D is the well known cutting

groove formed in C and with which engages a key E upon the tube B to ensure their integral rotation as aforesaid. F is the polishing roller held in frictional engagement 40 with the exterior of the tube A, by the cross-slide G of the movable saddle H of an ordinary lathe K, or the like.

What we claim as our invention and desire to secure by Letters Patent, is:—

1. The process of making seamless tubes which consists in concentrically winding a number of layers of wet paper pulp around a tubular member, allowing the pulp to dry, and bringing the pulp tube so formed into 50 frictional engagement with a rotatable member, whereby the pulp tube is simultaneously polished and loosened from the tubular member.

2. The process of making seamless tubes 55 which consists in concentrically winding a number of layers of wet paper pulp around a tubular member and allowing them to dry thereon; when in a dry state and during the rotation of the tubular member, bringing a rotatable member into frictional engagement with the said pulp tube whereby the latter is simultaneously polished and loosened from the tubular member; and applying a seamless metal rim at one end of the pulp tube and a seamless metal base at the opposite end of the pulp tube.

In testimony whereof we have signed our names to this specification.

WILSON WHITELEY.
WATSON WHITELEY.
